Primary Examiner — Christian P. McLean*Assistant Examiner* — Jessica Lynn Devilbiss(74) *Attorney, Agent, or Firm* — Renner, Otto, Boisselle & Sklar, LLP(57) **CLAIM**

The ornamental design for a tire tread, as shown and described.

DESCRIPTION

FIG. 1 is an enlarged partial front elevation view of a tire tread showing our new design;

FIG. 2 is a front elevation view thereof;

FIG. 3 is a front, right perspective view thereof;

FIG. 4 is a right side elevation view thereof; and,

FIG. 5 is a left side elevation view thereof.

The broken line showing is for the purpose of illustrating portions of the tire tread and forms no part of the claimed design.
